UNITED STATES PATENT OFFICE

141,205

DESIGN FOR AN EYESHIELD OR SIMILAR ARTICLE

Dexter P. Cooper, Jr., Hyde Park, N. Y., assignor to Polaroid Corporation, Cambridge, Mass., a corporation of Delaware

Application February 7, 1945, Serial No. 117,814

Term of patent 14 years

(Cl. D57—1)

To all whom it may concern:

Be it known that I, Dexter P. Cooper, Jr., a citizen of the United States, residing at Hyde Park, in the county of Dutchess and State of New York, have invented a new, original, and ornamental Design for an Eyeshield or Similar Article, of which the following is a specification, reference being had to the accompanying drawing, forming part thereof.

Fig. 2 is a top plan view of the same; and

Fig. 3 is a sectional view of the same, taken substantially along the line 3—3 in Fig. 1.

The essential features of my design reside in the parts shown in full lines, and the temples have been shown fragmentarily in Figs. 2 and 3 for convenience of illustration.

I claim:

The ornamental design for an eyeshield or similar article, substantially as shown and described.

DEXTER P. COOPER, JR.
